ABSTRACT: A tobacco smoke filter is provided for attachment to one end of a tobacco rod. The filter includes a pair of capsule-like cylindrical sections, each section having an upstream-facing open end and a downstream-facing closed end, the latter end having formed therein an axially-aligned hole. The sections are arranged in a partially telescoping relation with the closed ends thereof in longitudinally spaced relation and defining the end limits of an elongated cavity. Disposed within the cavity is a valve member biased to assume a hole-closing position with respect to the closed end of the upstream telescoping section. The valve member automatically moves to a hole-uncovering position upon a predetermined suction being applied to the downstream end of the filter. When the valve member is in its hole-uncovering position, the smoke is permitted to flow at a high velocity outwardly past the valve member and impinges against a cavity-forming surface and effects deposition thereon of liquid and solid smoke particles.

MECHANICAL TOBACCO SMOKE FILTER

This is a continuation of application Ser. No. 755,060, filed Aug. 26, 1968, now abandoned.

BACKGROUND OF THE INVENTION

Considerable effort has heretofore been expended in various attempts to develop a practical filter which would remove the liquid and solid smoke particles by utilizing the aerodynamics of the smoke stream so as to produce a smoke impingement effect. Although some encouraging results have been achieved with prior filters utilizing this phenomenon, such filters, however, have been plagued with production costs and operational problems and thus have not been generally accepted by the tobacco industry and the smoking public. The problems involving production costs arise to a large extent from the utilization of extremely small holes and/or tubes which were required to be precisely sized and located so as to effect the increased acceleration of the smoke velocity at certain locations within the filter. The operational problems, on the other hand, were caused by the extremely small holes and tubes becoming readily clogged or plugged shortly after the smoking had begun and thus producing a hard draw or high pressure drop across the filter.

SUMMARY OF THE INVENTION

Thus, it is an object of this invention to provide an impingement type smoke filter which does not require the utilization of a plurality of extremely small holes and/or tubes to impart a high velocity to the smoke flow.

It is a further object of this invention to provide an impingement type smoke filter which is of simple, inexpensive construction, effective in operation, and may be readily assembled by mechanical means, the function and operation of which are well known in the cigarette-making art.

It is a still further object of this invention to provide an impingement type smoke filter which may be readily adapted for use in cigarettes, cigars, pipe stems, or detachable cigarette and cigar holders.

It is a still further object of this invention to provide an impingement type filter which maintains a substantially constant pressure drop thereacross notwithstanding the smoking rate.

It is a still further object of this invention to provide an impingement type filter embodying an absorbent mass wherein the efficiency of the latter is materially increased.

Further and additional objects will appear from the description, accompanying drawings, and appended claims.

In accordance with one embodiment of this invention an impingement type smoke filter is provided which includes a pair of capsule-like cylindrical sections having upstream-facing open ends and downstream-facing closed ends. The closed end of each section is provided with a centrally disposed hole. The sections are arranged in a partial telescoping relation with the open end of the upstream section being affixed to one end of a tobacco rod. The closed ends of the telescoping sections define the end limits of an elongated cavity. Disposed within the cavity is a valve member which is biased to overlie and close off the hole formed in the closed end of the upstream section. When a predetermined suction is applied to the downstream end of the filter, the valve member will automatically move to a hole-open position whereby smoke will pass therethrough and then outwardly past said valve member at a high velocity and impinge against a cavity-forming surface causing liquid and/or solid particles entrained in the smoke to be deposited thereon.

DESCRIPTION

For a more complete understanding of the invention reference should be made to the drawings wherein:

FIG. 1 is a side elevational view of a filter cigarette embodying a preferred form of improved filter, the latter being shown in longitudinal section.

FIG. 2 is similar to FIG. 1, but showing the component parts of the filter in exploded relation.

FIG. 3 is similar to FIG. 1, but showing a modified form of the improved filter adapted to be detachably connected to one end of a tobacco rod.

Referring now to the drawings and more particularly to FIG. 1, a filter cigarette 10 is shown which embodies a preferred form of the improved impingement filter 11. The filter is affixed to one end of a tobacco rod 12, the latter comprising a core 13 of compacted shreds of blended tobacco, which is encompassed by a sleeve 14 of suitable cigarette paper.

Filter 11 in the illustrated embodiment includes a pair of capsule-like cylindrical sections 15 and 16. The sections are of like configuration and each includes an upstream-facing open end 15a or 16a and a downstream-facing rounded closed end 15b or 16b. The closed end in each instance is provided with a centrally disposed opening 15c or 16c which may vary in diameter size from approximately .031 inches to approximately .125 inches. The sections 15 and 16, if desired, may be formed from conventional plastic, double zero size medicinal capsule components. However, said sections also may be formed from other types of material such as foil, wax impregnated paper, etc.

25 The sections 15 and 16 are arranged in partial telescoping relation; that is to say the closed end 15b of the upstream section 15 is inserted approximately .250 inches into the open end 16a of the downstream section 16. By reason of this arrangement, an elongated cavity 17 is formed which is delimited by the closed ends 15b and 16b and the cylindrical wall 16d of section 16.

30 Positioned within cavity 17 is a valve member 18, which in the illustrated embodiment is in the form of a conventional plastic, single zero size capsule component. Other types of 35 valve members may be used, if desired, in place of the one illustrated. Valve member 18 is biased by a resilient piece 20 so that the open end 18a of member 18 overlies and closes off hole 15c formed in the closed end 15b of the section 15. The downstream end 18b of member 18 is closed and is engaged by 40 the resilient piece 20.

45 The resilient piece 20 may be formed of a suitable porous material such as sponge latex, or it may take the form of a spring. In any case, the resilient piece 20 should be so constructed as to permit the smoke to pass from the cavity 17, through the porous material and out through the hole 16c formed in the closed end 16b of section 16. The spring tension exerted by piece 20 on valve member 18 shall be such that the latter will move to its hole-opening position when the pressure differential is approximately 2-1/2 inches of H₂O.

50 Once the valve member has assumed its open position, the smoke will flow through hole 15c and then outwardly around the portion of the member 18 defining the open end thereof. Because the movement of the valve member is only a short distance, the annular opening, formed between the open end 55 of the valve member 18 and the closed end 15b of section 15 and through which the smoke must pass, is very narrow, thereby resulting in the velocity of the smoke passing therethrough being materially increased. In view of the high 60 velocity of the emitted smoke, the latter is caused to impinge against the interior surface of section portion 16d whereupon the liquid and/or solid particles entrained in the smoke are deposited thereon, prior to the smoke passing out through hole 16c.

65 Because of the movement of the valve member and the fact that the shape of the orifice or passageway through which the smoke is caused to flow is annular, there is no clogging or plugging up of the passageway by the smoke particles and thus no significant change occurs in the pressure drop across the 70 filter. Furthermore, the resilient piece 20 assures that the passageway maintains the proper dimension in order to produce desired smoke velocity. Thus, the need for small holes or tubes to attain the desired velocity is avoided.

If desired, an absorbent porous plug (e.g. Esteron fibers) 21 75 may be inserted within the open end of section 15 so as to be

disposed between the closed end 15b and the end of the tobacco rod 12. Prior to valve member 18 being moved to its open position, the smoke accumulates within section 15 and thus, the smoke more effectively permeates or is entrapped within the absorbent plug 21 enhancing the filtering efficiency thereof.

The capsule-like sections 15 and 16 are frictionally retained in their assembled relation and in turn are affixed to the adjacent end of the tobacco rod by a sleeve 22 of tipping paper or the like.

In the modified form 100 of the filter shown in FIG. 3, no sleeve is required to affix the sections to the end of the tobacco rod. To facilitate assembly of the filter 100 on the end of the tobacco rod or cigarette, the open end 115a of the capsule-like section 115 is flared outwardly a slight amount as seen in FIG. 3. To retain the two sections 115 and 116 in partial telescoping relation, the latter may be partially overwrapped by a sleeve 123 of suitable material such as paper or film.

Thus, it will be seen that an impingement type filter has been provided which is formed of a few inexpensive parts, is simple to assemble and is effective in removing liquid and solid particles from the smoke. The improved filter does not require a plurality of small carefully shaped and located holes or tubes through which the smoke is required to flow. The improved filter maintains a substantially uniform pressure drop thereacross regardless of the rate of smoking.

I claim:

1. A smoke filter adapted to be affixed to one end of a tobacco rod, said filter comprising an upstream hollow cylindrically shaped section and a downstream hollow cylindrically shaped section, said sections being arranged in partial telescoping relation, each section having an upstream-facing open end and a downstream-facing closed end, each closed end being provided with an aperture through which smoke

from the lighted tobacco rod is caused to flow upon a predetermined suction being exerted on the downstream end of the filter, the closed ends of said sections being in longitudinally spaced relation and defining the end limits of an elongated cavity; and a valve member and a resilient, porous-material bias means disposed within said cavity, said valve member being biased by said bias means to assume a closed position with respect to the closed end aperture formed in said upstream section, said valve member assuming an aperture-open position upon said predetermined suction being exerted on said filter downstream end, and cooperating with the adjacent closed end of said upstream section to form a narrow passageway through which the smoke flows at a high velocity and impinges against a cavity-forming surface and deposits thereon liquid and solid particles entrained in the smoke, and the smoke thereafter passing through the pores of said bias means.

2. The smoke filter of claim 1 wherein each telescoping section has a capsule-like configuration and the closed end thereof is substantially hemispherical.

3. The smoke filter of claim 1 wherein said bias means is disposed intermediate said valve member and the closed end of the downstream section and exerts a predetermined bias on said valve member.

4. The smoke filter of claim 1 including a mass of absorbent filter material disposed within the open end of said upstream section and adjacent the closed end of said upstream section, the smoke passing through said mass prior to passing through the aperture in said upstream section closed end.

5. The smoke filter of claim 1 wherein the portion of said upstream section delimiting the open end thereof is outwardly flared so as to facilitate insertion of an end of the tobacco rod into the upstream section open end.
